be rotated to a slight degree, causing a slight elevation of the sleeve 11 with respect to the sleeve 12. After a predetermined length of time, when the sleeve 12 is fully extended with respect to the sleeve 11, the motion may be reversed and the stilts caused to retract by reversing the direction of rotation. By using oppositely threaded stilts for opposite feet, the hands may be flexed in opposite direction in such manner that, for example, inward movement of the hands will cause extension of the stilts while outward movement will cause retraction or vice versa.

From the foregoing, it will now be seen that there is herein provided an improved amusement device affording a high degree of entertainment, which may be adjusted to a desired height before utilizing, and which may also be adjusted during the use thereof as above described.

It will also be seen that there is herein provided a device accomplishing all the objects of this invention and others including many advantages of great practical utility and amusement value.

As many embodiments may be made of this inventive concept, and as many modifications may be made in the embodiment hereinbefore shown and described, it is to be understood that all matter herein is to be interpreted merely as illustrative and not in a limiting sense, except as defined in the appended claims.

I claim:

1. In a stilt, the combination of an externally threaded sleeve, an internally and externally threaded second sleeve engaging with its internal thread the exterior threads of said first sleeve, an internally threaded third sleeve engaging the external threads of said second sleeve, stirrup means on said third mentioned sleeve, and means secured to one of said sleeves for causing relative rotation between two of said sleeves for longitudinally adjusting said stilt.

2. In a stilt, the combination of an externally threaded sleeve, an internally and externally threaded second sleeve engaging with its internal thread the exterior threads of said first sleeve, an internally threaded third sleeve engaging the ex-

ternal threads of said second sleeve, stirrup means on said third mentioned sleeve, and means secured to one of said sleeves for longitudinally adjusting said sleeves to vary the length of the stilt, said last mentioned means including a squared shank extending through said second sleeve and engaging said first sleeve, and means for securing said shank in fixed position with respect to said first sleeve.

3. A stilt comprising telescoping upper and lower sleeves, said upper sleeve having a stirrup thereon, said sleeves having a screw-threaded connection therebetween, an adjusting shaft rotatably but non-slidably engaging one of said sleeves and having a slidably but non-rotatable engagement with the other sleeve and extending exteriorly of said upper sleeve for effecting relative rotational and longitudinal adjustment of said stilt.

4. The combination of claim 3 wherein the lower sleeve is externally threaded and the upper sleeve is internally and externally threaded for engagement with the inner sleeve.

5. The combination of claim 4 wherein said upper sleeve has a third sleeve internally threaded and adjustable thereon, said third sleeve carrying said stirrup.

6. The combination of claim 3 wherein said upper sleeve has a third sleeve internally threaded and adjustable thereon, said third sleeve carrying said stirrup.

7. The combination of claim 3 wherein said adjusting shaft has a guide portion, said other sleeve having a guideway slidably receiving said guide, said guideway and guide being of non-circular cross section.
